UNITED STATES PATENT OFFICE.

WILLIAM O. SCHUMACHER, OF CHICAGO, ILLINOIS.

MATERNITY-SKIRT.

1,096,800.

Specification of Letters Patent. Patented Oct. 24, 1911.

Application filed February 23, 1911. Serial No. 610,190.

To all whom it may concern:

Be it known that I, WILLIAM O. SCHUMACHER, a citizen of the United States, residing at Chicago, in the county of Cook and State of Illinois, have invented a new and useful Improvement in Maternity-Skirts, of which the following is a specification.

My invention relates to an improvement in the class of skirts known as maternity-skirts, for concealing, or rendering less apparent, the wearer's abdominal enlargement.

The object of my invention is to provide a novel construction of skirt in the class referred to, which shall greatly increase its effectiveness for the purpose named.

In the accompanying drawings, Figure 1 illustrates my improved skirt by a broken perspective view; Fig. 2 is a broken view of the same in side elevation, and Fig. 3 is a broken view in elevation of a portion of the skirt showing the elastic portion of my improvement.

The material of the skirt proper 4 is plaited, as usual in skirts of the present kind. The rear section of the waist-portion of the skirt is sewed to the band 5 of an abdominal supporter 6 having extensions 7 and 8 attached to its forward edges by cords 9 laced through eyes 10 provided in the supporter and its extensions near their edges. By means of these fastenings the extensions may be let out as the width of the supporter is required to be increased. The supporter 6 is reinforced in its back-portion with vertical stays 11, and the meeting edges of the two extensions also have stiffening-stays sewed into them as indicated at 12, and are provided with fastenings 13, such as hooks and eyes, for releasably fastening the supporter along its front on the wearer.

The waist-portion of the skirt is permanently sewed to the band 5 nearly throughout its length, this sewed section extending from the point at 14, near one end of the band, to an inch or more short of the opposite end thereof, as to the point at 15, whence the skirt is free to form the flap 16 thereof (Fig. 1); and the waist-band 17 of that section has gathered upon it, to extend longitudinally thereof, a cloth-covered elastic strap 18. At intervals along the inner face of the strap are provided eyes 19 to engage with buttons 20, or hooks provided in proper position at intervals along the upper-edge portions of the extensions 7 and 8.

One, separate, section 21 of an external

finishing or "crush" band or belt is permanently sewed to the band 5 to extend from one point 14 to the other 15, and is provided with series of eyes 22 and 23 extending, respectively, from its opposite ends toward the center of the back of the waist. Another section, 24, of the crush-band is sewed, midway between its ends, to the skirt and elastic strap 18, about midway between the ends of the latter, to hang, when out of use, as represented in Fig. 1, the ends of this section being shown to be provided with ornamental buttons 25 and with hooks 26 and 27 to engage, respectively, with the eyes 22 and 23.

It will be observed that the back-portion of the supporter 6 is considerably longer, vertically, than either of its similar extensions, 7 and 8, to cause it to reach higher at its center on the back of the wearer; and that from that center it slopes gradually in opposite directions toward its ends to which the extensions are laced. That construction is an important feature of my improvement in serving the purpose hereinafter explained.

When my improved skirt is worn, for the first time, supposing no material abnormal abdominal enlargement of the wearer to have yet taken place, the parts of the skirt may be in their initial or normal relative positions in which they are represented in Fig. 1, except that the edge of the flap 16 will be fastened by the hooks and eyes 13, and the ends of the crush-band section 24 will be hooked, respectively, to the eyes 22 and 23 at the back-ends of the series thereof. As the enlargement, referred to, progresses, the extensions 7 and 8 are let out sufficiently to compensate therefor, and the strap 17 is stretched adequately to cause it and the flap 16 to bridge the increased expanse and be fastened by the hooks and eyes at 13. Then the ends of the crush-band section 24 will engage at their hooks, 26, 27, eyes 22 and 23 nearer the front ends of the series thereof, and the eyes first used may be removed to avoid their display. The same operations will be repeated as the requirement for expansion of the supporter-portion of the skirt occurs.

The provision of the abdominal covering of the skirt in the form of an expansibly-adjustable supporter affords a desirable support to the part of the body in abnormal condition and tends to cause the skirt to hang properly and without liability to creep upwardly at the waist, to seek lodgment

above the protruding portion of the body; and this tendency is materially assisted by the described slant afforded to the supporter 6, since thereby it better supports the back 5 of the wearer and thus avoids the disposition to lean backwardly, in standing, in the sub-conscious desire to relieve the abdominal weight, but which also raises the front part 10 of the skirt and helps to disarrange the waist-portion and to defeat the purpose of the maternity-skirt.

What I claim as new, and desire to secure by Letters Patent, is:—

1. In combination, a skirt having a plaited flap-portion, an extensible strap on said flap-portion, an abdominal supporter on the skirt to encircle the body of the wearer and formed of back and front sections, and means fastening said sections together to 20 adapt the supporter to be let out for expanding it, the front portion of said supporter being of a length to extend from the waist-line of the skirt over the receding portion of the wearer's abdomen, for the purpose set forth.

2. In combination, a skirt having a plaited flap-portion, an extensible strap on said flap-portion provided with means for fastening its free end, an abdominal supporter 30 on the skirt to encircle the body of the wearer and formed of back and front sections, and means fastening said sections together to adapt the supporter to be let out for expanding it, the supporter being 35 of a length to extend its back-portion from the waist-line of the skirt approximately to the line of the wearer's hips and its front portion from said waist-line over the receding portion of the wearer's abdomen, and 40 said back-portion being highest at its center and sloping thence in opposite directions toward the front, for the purpose set forth.

3. In combination, a skirt having a plaited flap-portion, an abdominal supporter 45 comprising a back-section secured to the

skirt and two front-sections laced to the back-section to adapt them to be let out for expanding the supporter, means for fastening said front-sections together at their front ends, and an extensible strap secured to said flap-portion and provided with means for fastening its free end, for the purpose set forth.

4. In combination, a skirt having a plaited flap-portion, an abdominal supporter 55 comprising a back-section secured to the skirt and two front-sections laced to the back-section to adapt them to be let out for expanding the supporter, means for fastening said front-sections together at their 60 front ends, a crush-band section on said back-section provided with eyes, an elastic strap secured to said flap-portion and provided with means for fastening its free end, and a crush-band section secured between 65 its ends to the flap and provided on its ends with hooks to engage said eyes, for the purpose set forth.

5. In combination a skirt having a plaited flap-portion, an abdominal supporter on 70 the skirt comprising a back-section secured to the skirt and two front-sections laced to the back-section to adapt them to be let out for expanding the supporter, and provided with means for fastening together their 75 front ends, said back-portion being highest at its center and sloping thence toward said front-sections; a crush-band section on said back-section provided with eyes, an elastic strap secured to said flap-portion and provided with means for fastening its free end, and a crush-band section secured between its 80 ends to the flap and provided on its ends with hooks to engage said eyes, for the purpose set forth.

WILLIAM O. SCHUMACHER.
